[57] CLAIM

The ornamental design for a data processing terminal, as shown and described.

DESCRIPTION

FIG. 1 is a front perspective view of a data processing terminal, showing our new design;

FIG. 2 is a rear elevational view thereof.

The side of the display terminal which is not shown is a mirror image of the side shown in FIG. 1.

The characteristic feature of our design resides in the recessed, contrasting groove which is diagonally disposed around the upper portion of the terminal housing.
